[57] CLAIM

The ornamental design for a cargo storage restraint, as shown and described.

DESCRIPTION

FIG. 1 is a perspective view of a cargo storage restraint, showing my new design, with a portion of an automobile trunk and articles positioned therein in broken lines for illustrative purposes only and form no part of the claimed design;

FIG. 2 is an enlarged front elevational view thereof;

FIG. 3 is an enlarged rear elevational view thereof;

FIG. 4 is an enlarged elevational view of one side thereof;

FIG. 5 is an enlarged elevational view of an opposite side thereof;

FIG. 6 is an enlarged top plan view thereof; and,

FIG. 7 is an enlarged bottom plan view thereof.

*Fig. 1**Fig. 2**Fig. 3**Fig. 6**Fig. 4**Fig. 5**Fig. 7*
